UNITED STATES PATENT OFFICE.

WALTER H. HIMES, OF WILKINSBURG, PENNSYLVANIA, ASSIGNOR TO WESTINGHOUSE ELECTRIC & MANUFACTURING COMPANY, A CORPORATION OF PENNSYLVANIA.

PIPE-THREADING MACHINE.

Application filed May 8, 1926. Serial No. 107,814.

This invention relates generally to improvements in pipe-working machines and more particularly to portable power-driven pipe threading machines.

5 The object of the invention generally stated, is the provision of a portable pipe threading machine that shall be simple and efficient in operation and readily and economically manufactured.

10 A more specific object of the invention is to provide for the use of the casing of a portable threading machine as a lever for holding the machine during the operation of the stocks and dies.

15 A further object of the invention is the provision of a portable threading machine that may be taken apart and assembled with facility to permit examination and repairs.

20 It is also an object of the invention to provide for reducing the distance between the guide and dies to a minimum while still retaining proper driving connections to permit the threading of short lengths of pipe.

25 Other objects of the invention will in part be obvious and in part appear hereinafter.

30 The invention accordingly is disclosed in the embodiment thereof shown in the accompanying drawing and comprises the features of construction, combination, of elements and arrangement of parts which will be exemplified in the construction hereinafter set forth and the scope of the application of which will be indicated in the claims.

35 For a full understanding of the nature and objects of the invention, reference may be had to the following detailed description taken in conjunction with the accompanying drawing in which,

40 Figure 1 is a view, partially in section and partially in side elevation, showing a portable pipe threader constructed in accordance with this invention.

45 Figure 2 is a section along the line II-II of Fig. 1 showing features of construction of the pipe threader.

50 Referring now to the drawing, 10 designates generally a main casing which in this particular construction is in two parts, 11 and 12. The lower section of the casing is provided with a removable end plate 13 to permit the mounting of a motor 14 therein.

55 In order to facilitate the using of the machine, a handle 15 is pivotally mounted on the removable plate 13, and disposed to

swing in a predetermined plane so that it may be set in any desired position for holding the casing during operation.

The casing section 11 is shaped for the reception of a train of reduction gears of the type shown in copending application, Serial No. 703,675, filed April 2, 1924 in the name of H. D. Else. In connecting the two casing sections any method may be adopted, such as providing them with flanges and connecting the flanges by means of bolts or the like.

60 In this construction, a spider 16 is provided in the casing section 10 to support a bearing 17 for the motor shaft 18. As shown, the motor shaft 18 extends through both casing sections and carries a pinion gear 19 which serves to drive a train of gears that will be described hereinafter.

65 The train of reduction gears provided comprises a ring gear 20 fixed in position in the casing section 11 and a plurality of planetary gears 21 which are carried by the frame 22 and disposed to mesh with the ring gear 20 and the sun gear 19. Loosely mounted on the upper ends of projections provided on the frame 22 are a plurality of planetary gears 23 which mesh with a ring gear 24 that has formed integral therewith, a cap 25 which is fixed to shaft 26. In order to transmit power from the train of planetary gears, a pinion gear 27 is fixed on the upper end of the shaft 26.

70 The auxiliary casing 28 comprises two sections 29 and 30. As shown, the section 29 has provided on its lower end a flanged portion shaped to seat on the upper end of the main casing 10, and it may be fixed in position in any suitable manner, such as by the use of bolt screws 31. In this particular construction, the section 30 comprises a plate which is adapted to be removably mounted in the casing section 29 to permit access to the auxiliary casing 28 for the installation of the operating gears.

75 In order to mount the stocks and dies, shown generally at 32, a sleeve 33 is rotatably disposed in the auxiliary casing 28 to extend at right angles to the motor shaft. As shown, this sleeve is rotatably mounted in bearings 33' formed in the auxiliary casing sections 30 and 29, respectively.

80 As shown, the sleeve 33 is driven from the pinion 27 by means of a ring gear 34 which is fixed to the sleeve 33 by means of a key

39. By providing a bevelled ring gear 34 and a bevelled pinion 27, the auxiliary casing 28 may be easily and quickly removed from the main casing 10 for the purpose of making repairs and replacement of parts. Further, when the casings are properly connected positive engagement is established between the two gears.

The stocks and dies 32 which may be of 10 any well-known construction, may be fixed to the sleeve 33 by means of a plurality of set screws 35. In order to guide pieces of pipe, such as 36, into the dies, an adjustable pipe guide 37 is mounted at the opposite end 15 of the sleeve 33 from the stocks and dies.

It will be readily understood that by providing a ring gear for driving the sleeve that the distance between the guide and stocks and dies may be reduced to a minimum 20 to permit the threading of short pieces of pipe. This construction also assures an efficient drive since the ring gear is positioned close to the dies 1.

Further, it will be seen that the stocks 25 and dies have axes about which they rotate, the axes extending at right angles to the shaft of the motor and to the longitudinal axis of the substantially cylindrical casing 10. Accordingly, the casing may be used to 30 hold the threader during operation.

In operation, when a pipe section or the like is mounted in any support, such as the vice 38, the portable pipe threader is then mounted on the end of the pipe and the dies 35 engaged. When the motor is set in operation and the dies begin to cut, there is a tendency for the machine to swing around the axis of the pipe. In this construction, the threader may be held by means of the 40 casing which serves as a lever.

As will be readily understood when the machine tends to turn about the axis of the pipe, it does so upon the exertion of a force, a component of which acts at right angles 45 to a line drawn between the axis of the stocks and dies and the handle 15 and intermediate of these points. Thus it will be seen that the casing may be utilized as a lever for the holding of the machine during the 50 operation of the dies.

Further it will be readily understood that the motor may be controlled in any well known manner to rotate the stocks and dies in either direction. Thus a portable threading 55 machine, adapted for the threading of pipes of small diameter and the like may be constructed.

Since certain changes may be made in the 60 above construction and different embodiments of the invention may be made without departing from the spirit thereof, it is intended that all matter contained in the

above description, or shown in the accompanying drawing, shall be interpreted as illustrative and not in a limiting sense.

65

I claim as my invention:

1. In a power-driven portable threading machine, in combination, a main casing, a motor and a motor-driven train of reduction gears carried by the main casing, an auxiliary casing mounted on the end of the main casing, a sleeve rotatably mounted in the auxiliary casing, stocks and dies and a pipe guide mounted on opposite ends of the sleeve, a bevelled ring gear fixed to the 70 sleeve at a point between the pipe guide and stocks and dies, and a bevelled pinion gear actuated by said train of gears disposed to engage the ring gear when the auxiliary casing is in position on the main casing, the 75 axis of the main casing extending substantially at right angles to the axis of the sleeve, whereby the casing may be used as a lever for holding the machine during the 80 operation of the stocks and dies.

85

2. In a portable threading machine in combination, a main casing, a motor and motor driven train of gears carried by the casing, a bevelled pinion gear driven by the train of gears, said pinion extending beyond 90 the casing, an auxiliary casing adapted to be removably mounted on the main casing, a sleeve rotatably mounted in the auxiliary casing, a set of stocks and dies and a pipe guide mounted on opposite ends of the sleeve 95 and a bevelled ring gear fixed to the sleeve between the guide and dies, said ring gear being disposed to engage the pinion when the auxiliary casing is mounted in position on the main casing.

100

3. In a portable threading machine in combination, a main casing, a motor and a motor-driven train of gears carried by the casing, a bevelled pinion gear driven by the train of gears, said pinion extending beyond 105 the casing, an auxiliary casing adapted to be removably mounted on the main casing, a sleeve rotatably mounted in the auxiliary casing, a set of stocks and dies and a pipe guide mounted on opposite ends of the sleeve 110 and a bevelled ring gear fixed to the sleeve between the guide and dies, said ring gear being disposed to engage the pinion when the auxiliary casing is mounted in position on the main casing.

115

In testimony whereof, I have hereunto 120 subscribed my name this first day of May, 1926.

WALTER H. HIMES.
